UNITED STATES PATENT OFFICE.

CHARLES LEJEUNE, OF WOLUWE-ST. LAMBERT, NEAR BRUSSELS, BELGIUM, AS
SIGNOR TO JULES LEJEUNE, OF BRUSSELS, BELGIUM.

CONTROL VALVE.

Application filed April 18, 1922. Serial No. 555,046.

To all whom it may concern:

Be it known that I, CHARLES LEJEUNE, a subject of the King of the Belgians, residing at Woluwe-St. Lambert, near Brussels, 5 in the Kingdom of Belgium, have invented certain new and useful Improvements in Control Valves, of which the following is a specification.

This invention relates to a control valve especially adapted for use on locomotives, but which may also be applied to stationary machines or to any other type such as for example hydraulic cranes.

Control valves with double seats such as 15 commonly employed principally in locomotives, present many difficulties chiefly in obtaining a perfectly steam tight joint as well as the impossibility of obtaining gradual opening. In the case of a locomotive for 20 example these inconveniences show themselves by swaying of the machine, violent starting and the production of serious damage due to the sudden starting followed by very pronounced condensation of the steam 25 in the cylinders.

These inconveniences make slide valve control preferable to ordinary double seated valve control.

Slide valves also have their own inconveniences amongst which the principal are the intense swirling of the steam and the impossibility of cutting off admission in 30 case of a break down of the controls.

The object of this invention is to overcome 35 both the inconvenience of control valves of this type and also of slide valves.

With this object in view the invention essentially consists in a special arrangement of a plurality of independent valves 40 as will be hereinafter fully described and pointed out in the appended claims.

Referring to the accompanying drawing which shows by way of example, one form of the invention:

Fig. 1 is a sectional elevation of a multiple control valve for a machine of medium power.

Fig. 2 is a plan view of same.

The valve shown, more particularly applicable for locomotives is placed as is usual in the steam dome of the boiler. It is made up of a circular casing 1 having a lateral extension affixed by a flange 2 and bolts 3 to the pipe 4 and so to the machine.

In the upper end of the casing are circular

openings 5 forming seatings 6 for the valves 7; there are six shown on the drawings but this number may be increased or diminished and may be eight for high power machines. Through the centre of the casing 1 is formed 60 a sleeve or central guide 8 through which passes the rod 9 affixed at its lower end to the ordinary operating rod of the control valve. Arms 10 are formed on the upper part of the rod 9. There are as many arms 10 as there are openings 11, through which pass the stems 12 of the valves 7.

In the drawing shown the effective lengths of the stems 12 of the various valves are different and may be adjusted by nuts 13 70 against which the arms 10 bear when the rod 9 is raised vertically. Under these conditions the valve having the least length of stem between its base 14 and the nuts 13 will open first, on the commencement of 75 any movement of the rod 9 in the vertical direction, whilst the next valve will only be lifted from its seating when the first has been raised a distance corresponding to the difference in lengths of the stems between 80 the base and the nuts. Hence if the arrangement consists of eight valves, for example, the regulation may be such that the first may be raised nine millimetres when the eighth has only been raised one millimetre. The casing being housed in the steam dome the steam will penetrate into the annular space 15 as soon as the first valve is 85 opened. This annular space 15 in the shape of a horse shoe, surrounds the central guide 90 8. At the time of closing the control valve, that is to say when the control rod 9 is lowered the valves will be returned to their seatings and held there, without the possibility of any of the valves opening unintentionally.

In such an arrangement the valves open successively and it is evident that the pressure to be overcome to open them is reduced to that necessary to open a single 100 valve with the consequent advantage of reducing the mechanical power employed and rendering the operation more simple.

The order in which the valves open may be regulated at will, nevertheless an order is adopted, such that two valves placed at the extremities of a diameter open successively in order to obtain the best distribution of the steam.

It is evident that the invention is not 110

2
limited to the details of construction in the arrangement shown, for example the regulations of the valves for opening successively may be effected by means of washers of 5 variable thickness placed on the stems 12 between the arms 10 and the nuts 13, the nuts 13 being uniformly spaced at the same distance from the bases 14.

What I claim is:

- 10 1. In a control valve for steam engines, a casing the said casing being provided with a number of holes, each hole forming a seating for a valve, a valve for each hole adapted to close the same a guide arranged 15 centrally in the casing, a single control rod passing through said guide, arms projecting from the said control rod and means whereby the said arms act successively on the valves to open the same in succession when 20 the control rod is acted upon.
2. In a control valve for steam engines, a casing, the said casing being provided with a number of holes arranged circularly a valve seat formed in each of the said holes, 25 a valve for each of the said holes, a guide arranged centrally in the casing, a single control rod passing through the said guide and projecting centrally above the casing, arms projecting radially from the control 30 rod and adjustable abutments carried by

the valves, the said abutments cooperating with the radially projecting arms whereby the valves may be opened in succession when the control rod is acted upon.

3. In a control valve for steam engines, 35 a circular casing having a lateral extension, a connecting flange at the end of said extension, the said casing being provided in its upper end with a number of holes arranged circularly around the center of the 40 casing, a valve seat formed in each of the said holes, a sleeve extending centrally in the casing from the upper to the lower end of said casing, a single control rod guided in said sleeve and projecting above the upper 45 end of the casing, arms projecting radially from the control rod, a valve in each hole of the casing each valve being provided with a stem passing through a corresponding projecting arm of the control rod and adjustable abutments on the said valve stems 50 whereby the valves are adapted to be opened in succession when the control rod is acted upon.

In testimony whereof I have affixed my 55 signature in presence of two witnesses.

CHARLES LEJEUNE.
